UNITED STATES PATENT OFFICE.

ROBERT O. HENDRICKSON, OF RACINE, WISCONSIN, ASSIGNEE TO WALLIS TRACTOR COMPANY, OF RACINE, WISCONSIN, A CORPORATION OF WISCONSIN.

VALVE-ACTUATING MECHANISM.

1,378,111.

Specification of Letters Patent. Patented May 17, 1921.

Application filed March 15, 1917. Serial No. 154,938.

To all whom it may concern:

Be it known that I, ROBERT O. HENDRICKSON, a citizen of the United States, residing at Racine, in the county of Racine and State of Wisconsin, have invented certain new and useful Improvements in Valve-Actuating Mechanism, of which the following is a specification.

My invention relates more particularly to 10 valve mechanism for that type of explosion engine in which a puppet valve is located in the head thereof. By my improvement lubrication of the actuating parts is to a considerable extent dispensed with and unnecessary friction of the parts avoided. While 15 I have shown and described the invention as applied to a specific type of engine, it will be understood that the invention is applicable in other connections which will 20 suggest themselves to those skilled in the art to which the invention relates.

In the drawing Figure 1 is a longitudinal central section of so much of an explosion engine as is necessary to understand my invention; showing the latter applied thereto, and Fig. 2 is a section of a detail, parts being shown in elevation.

The cylinder 3, piston 4, cylinder head 5, valve 6 and valve spring 7 are or may be of 30 well known types except in so far as they are modified in the respects heretofore pointed out. The valve stem 6' as usual projects through the head of the cylinder and is operated by a rocking lever 8 which 35 is journaled at 9 to a standard 10 on the cap 27 of the motor in a well known manner. The valve operating shaft 11 is as usual located in the crank case and has one or more cams 12 thereon, according to the number 40 of valves to be operated.

Registering cylindrical passages 13, 14 are cast in the water jacket and cylinder head, respectively, for the push rod 15 by 45 which motion is transmitted from the valve shaft to the rocker arm 8. At its lower end the push rod 15 rests in a cupped follower 16 which is guided in a bearing 17 in a bracket 18 cast integral with the casing, the interior of the follower being cupped 50 and formed with a conical bottom 19 on the bottom of which the push rod rests loosely. The upper end of the push rod is threaded at 20 to receive an interiorly threaded sleeve 21 which is adjustable on 55 said rod and formed at its upper end with

a partially spherical cavity 22 which receives the ball 23. A lock nut 24 holds the sleeve in adjusted position. The rocker arm 8 is formed at 25 with a partially spherical bearing of a size to fit the ball 23 and is further formed with a funnel-shaped opening 26 communicating with the ball seat for the purpose of receiving oil and feeding it to the ball.

The pressure of the valve spring 7 against 65 the valve rod is communicated to the rocker arm and thereby exerts a constant pressure upon the ball so that no opportunity is given for the ball to leave its seat accidentally. In disassembling the engine for any 70 purpose the rocker arm is simply lifted off with the part to which it is attached, in this instance the cover casting 27, and if desired the ball and push rod may be lifted 75 out, there being no couplings or joints to uncouple. The push rod is held at its ends between the ball and the follower, no bearings being required except the follower bearing in the crank case, thus simplifying the 80 question of lubrication and guiding of said rod. The ball being free to revolve when the valve comes to its seat presents constantly new surfaces for wear so that the joint between the rocker arm and the push 85 rod is of long life and the parts need renewal but seldom. The funnel-shaped opening 26 receives sufficient oil from that atomized by the movement of the oiled parts within the crank case to thoroughly lubricate the ball.

I claim:

1. In a device of the class described, a spring-pressed valve, a rocker arm for operating the valve there being a partially spherical socket formed in said arm, a push 95 rod for operating said rocker arm, a sleeve threaded upon said push rod and having a partially spherical socket in its upper end and a ball seated in the sockets in said sleeve and rocker arm respectively.

2. In a device of the class described, in combination with the piston and cylinder thereof, a jacket surrounding the cylinder having a passage therethrough, a cylinder cap having a passage registering with the passage in the jacket, a spring-pressed valve in said cylinder cap, a rocker arm mounted on said cap for operating the valve, a cam for operating said rocker arm and a push rod actuated by said cam extending loosely 110

through said passages and having a ball-and-socket joint with said arm.

3. In a device of the class described, in combination with the piston and cylinder 5 thereof, a jacket surrounding the cylinder having a passage therethrough, a cylinder cap having a passage registering with the passage in the jacket, a cover plate secured to said cylinder cap, a spring-pressed valve 10 in said cylinder cap, a rocker arm mounted

on said cap within said cover plate for operating the valve, said rocker arm being formed with a partially spherical socket on its under side and a funnel-shaped opening on its upper side communicating with said 15 socket, a push rod extending loosely through said passages and having a ball connection with said socket, and means for operating said push rod.

ROBERT O. HENDRICKSON.
